UNITED STATES PATENT OFFICE

ALBERT A. CHANEY, OF JEWETT, OHIO

FOLDING SEAT

Application filed May 26, 1927. Serial No. 194,375.

This invention is a folding seat intended primarily for use upon grand stands, circus seats and like structures although it is also adapted for use upon a chair frame. The object of the invention is to provide an inexpensive and durable seat which will be comfortable and which when not in use may be so disposed as to protect the surfaces from the weather and also permit the passage of 10 sight-seers through the aisles in front of and back of a row of seats. A further object of the invention is to provide a seat for the stated purpose which will be so constructed and mounted that it may rock freely under 15 the movements of the user so that the fatigue due to protracted sitting in one position will be relieved. Other objects of the invention will appear incidentally in the course of the following description, and the invention re- 20 sides in certain novel features which will be particularly pointed out in the appended claims.

In the accompanying drawings:

Figure 1 is a perspective view showing one 25 embodiment of the invention;

Fig. 2 is an enlarged rear elevation of a corner showing the connection between the seat proper and the back;

Fig. 3 is a side elevation showing the position of the parts when the user rocks;

Fig. 4 is a side elevation showing the device in collapsed condition, and

Fig. 5 is a side elevation showing the invention applied to a chair frame.

In the drawings, the reference numeral 1 indicates a bench of a stadium or grand stand or the main supporting frame of circus seats. This bench is ordinarily provided with a top 2 of planks, and in carrying out my invention 25 in its most generally adopted form, a supplemental plank or board 3 is secured over the permanent plank 2 by screws, as indicated. The screws may obviously be removed at will so that, when the invention is applied to 40 structures which have seasonal use the seat board 3 may be removed from the bench and the seats mounted upon said board stored bodily until the next season opens. Arranged along the seat board 3 at or near the 45 rear edge thereof and at intervals along the

same are secured brackets 4 having upstanding inverted U-shaped end portions 5 which provide bearings for the pivots or trunnions of the backs of my improved seats. It will be noted upon reference to Figs. 1 and 2 that 55 the back is provided with a laterally extending trunnion or pivot engaged in the outer end portion of the bearing member 5 and that the said bearing portion 5 constitutes a cover for the end of the pivot or trunnion 60 so that persons passing back of the bench and the seats thereon are not apt to be injured by contact with the trunnions nor to have any portion of their clothing damaged from the same source. The chair or seat of my in- 65 vention comprises a seat member, indicated at 6, and a back, indicated at 7. Each of these members comprises a sheet metal plate 8 of proper dimensions having its edge por- 70 tions rolled upon itself to form a bead 9 on its under or rear side and engaged around a bracing and carrying frame consisting of a light rod or stout wire 10 formed into substantially U-shape with its bight portion disposed at the outer or upper edge of the 75 sheet metal plate and its side portions dis- posed at the sides of said plate. The frame of the back has its side members extended beyond the lower edge of the back and inset, as shown at 11; the inset portions 11 terminat- 80 ing in outwardly projecting trunnions or pivots 12 which engage through openings provided therefor in the bearing portions 5 of the securing brackets. The frame of the seat member has its side portions also ex- 85 tended beyond the rear edge of the plate 8 and then each formed into a coil 13 imme- diately adjacent the rear edge of the said plate and encircling the adjacent pivot or trunnion 12, as shown in the drawings. The convolu- 90 tions of the coil 13 are so disposed that the coil extends inwardly relative to the side of the frame and it may be given one or more turns as may be desired, but in any event will terminate in an upwardly and rearward- 95 ly projecting finger 14 which normally bridges the inset portion 11 of the back frame and has its extremity disposed imme- diately in rear of the upper end of said inset portion whereby the back frame will rest 100

against the fingers 14 and will be thereby prevented from dropping backwardly. The fingers 14 are disposed at an angle to the side members of the seat frame somewhat greater than a right angle so that, when the device is in use, the back will be supported at an inclination which will support the back of the user without discomfort. It will be readily noted that the engagement of the pivots or 10 trunnions 12 with the bearing members 4 constitute the sole means of attaching the device to the bench 3 and, therefore, the seat and back members may have a rocking movement as a unit about the trunnions or pivots, 15 as shown in Fig. 3, but cannot be detached therefrom without the exercise of considerable effort in order to release the trunnions from the bearing brackets. The user of the device may, therefore, lean backwardly to a 20 reasonable extent and overcome fatigue, the backward pressure exerted upon the back 7 being transmitted through the insets 11 and the terminal fingers 14 to the seat, but the natural position of the feet and legs of the 25 user will prevent the rocking movement extending so far as to upset the occupant. When the use of the device is temporarily discontinued, the back may be swung down onto the seat member, as shown in Fig. 4, 30 so that the aisles in front and in rear of the bench 2 will be cleared and the former occupants of the seats may readily pass out. When the season for the use of the device is closed, the board 3 is removed and the row 35 of seats secured thereon may then be stored as an entirety until the ensuing season opens.

While my device is obviously desirable for use in stadiums and grand stands erected for exhibitions and competitions in athletics and other similar amusements, it may be applied 40 to chair frames and in Fig. 5 I have illustrated such an application of the invention. When the device is to be thus employed, the trunnions 12 are inserted through the upper 45 rear ends of leg members 15 in the same manner that they are inserted into the bearing members 5 in the previously described arrangement. The chair frame may be of any desired construction and, for the sake of illustration, I have shown a chair frame comprising 50 legs 15 pivoted together between their ends and locked against spreading by a foldable brace 16. The legs may be folded together when the device is not in use so that the 55 entire chair may be arranged within a small compass. The upper ends of the front legs may be equipped with any desired or approved means for engaging the forward edge of the seat member or supporting the same so 60 that the seat member will be firmly held in proper position for use. No change in the arrangement or construction of any of the parts of the device is required to fit it to the chair frame, the only change being the substitution of a chair frame for the brackets 4.

Having thus described the invention, I claim:

1. A seat comprising a relatively fixed support, a back member including a frame having side members constructed with insets at 70 their lower ends and terminating in outwardly projecting pivots engaged with the fixed support, and a seat member including a frame disposed entirely in a single plane and having side members extending beyond the rear edge 75 of the seat member and constructed with elements loosely encircling the said pivots and terminating upwardly in fingers extending in angular relation to the said encircling elements of the side members back of the insets 80 of the back member whereby to limit the rocking movement of the back independently of the seat and effect rocking of the seat and back as a unit.

2. A seat comprising a seat board adapted 85 to be secured upon a fixed support, brackets secured at intervals upon said board near the rear edge thereof, said brackets having upstanding terminals constituting bearing members, a seat back including a frame having insets at its lower end terminating in outwardly projecting pivots engaged in said terminals of the brackets, and a seat including a frame disposed entirely in a single plane adapted to rest upon the seat board and provided with 90 coils loosely encircling said pivot members and terminal fingers extending from the coils at an angle to the seat in rear of the insets 95 whereby the back member may fold over onto the seat member or swing rearwardly and 100 engage said terminal fingers and impart rocking movement to the seat member.

In testimony whereof I affix my signature.
ALBERT A. CHANEY. [L. S.]
